US0D1006792S

(12) **United States Design Patent** (10) **Patent No.:** **US D1,006,792 S**
(45) **Date of Patent:** **** Dec. 5, 2023**

(54) **REMOTE CONTROLLER**

(71) Applicant: **Hiroyasu Kosuge**, Osaka (JP)

(72) Inventor: **Hiroyasu Kosuge**, Osaka (JP)

(73) Assignees: **DAIKIN INDUSTRIES, LTD.**, Osaka (JP); **DAIKIN EUROPE N.V.**, Ostend (BE)

(**) Term: **15 Years**

(21) Appl. No.: **29/808,967**

(22) Filed: **Sep. 24, 2021**

(30) **Foreign Application Priority Data**

Mar. 30, 2021 (EM) 008480628-0001

(51) **LOC (14) Cl.** **14-03**

(52) **U.S. Cl.**

USPC **D13/168**; D14/218

(57) **CLAIM**

The ornamental design for a remote controller, as shown and described.

DESCRIPTION

FIG. 1 is a perspective view of a remote controller showing my new design;

FIG. 2 is a front view thereof;

FIG. 3 is a rear view thereof;

FIG. 4 is a plan view thereof;

FIG. 5 is a bottom view thereof;

FIG. 6 is a left side view thereof;

FIG. 7 is a right side view thereof; and,

FIG. 8 is a reference view of the usage state showing a display portion.

The broken lines depict portions of the remote controller that form no part of claimed design.

1 Claim, 3 Drawing Sheets
